(57) **CLAIM**

The ornamental design for clay bird thrower, as shown and described.

DESCRIPTION

FIG. 1 is a perspective view of a clay bird thrower in accordance with an embodiment of the invention;

FIG. 2 is a top view of the embodiment shown in FIG. 1;

FIG. 3 is a right side view of the embodiment shown in FIG. 1;

FIG. 4 is a bottom view of the embodiment shown in FIG. 1;

FIG. 5 is a left side view of the embodiment shown in FIG. 1;

FIG. 6 is an end view of the embodiment shown in FIG. 1; and,

FIG. 7 is an end view of the embodiment shown in FIG. 1.

The broken line showing of a clay bird disc is included for the purpose of illustrating environment and forms no part of the claimed design.
